(57) **CLAIM**

The ornamental design for a vehicle window breaker with seatbelt cutter, as shown and described.

DESCRIPTION

FIG. 1 is a front, left and top perspective view of a vehicle window breaker with seatbelt cutter showing my new design;

FIG. 2 is a rear, right and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is an enlarged top plan view thereof;

FIG. 8 is an enlarged bottom plan view thereof;

FIG. 9 is an exploded front, left and top perspective view thereof;

FIG. 10 is an exploded rear, right and bottom perspective view thereof;

FIG. 11 is an exploded front elevation view thereof;

FIG. 12 is an exploded rear elevation view thereof;

FIG. 13 is an exploded left side elevation view thereof;

FIG. 14 is an exploded right side elevation view thereof;

FIG. 15 is an exploded top plan view thereof; and,

FIG. 16 is an exploded bottom plan view thereof.

The broken lines in the drawings depict portions of the vehicle window breaker with seatbelt cutter that form no part of the claimed design.
